UNITED STATES PATENT OFFICE.

WILLIAM D. SKIDMORE, OF PELHAM, NEW YORK.

DUMPING-CAR.

1,171,470.

Specification of Letters Patent. Patented Feb. 15, 1916.

Application filed November 3, 1914. Serial No. 870,072.

To all whom it may concern:

Be it known that I, WILLIAM D. SKIDMORE, a citizen of the United States, and a resident of Pelham, Westchester county, 5 State of New York, have invented certain new and useful Improvements in Dumping-Cars, of which the following is a specification.

My invention relates to railroad cars, and 10 more particularly to that class of cars known as dumping cars, such as are used, for instance, in railroad construction, for conveying ballast, filling material, and the like to such places as the same may be needed, and 15 dumping the same upon or at the side of the right of way; but it will be readily understood that cars constructed according to my invention may be used for other purposes as well as those above specified.

20 The object of my invention is to provide a car which shall be simple in construction, and at the same time efficient and easy of operation, and which shall be adapted to dump its load either quickly and all at the 25 one time, or slowly and at a predetermined rate of discharge, and in which the adjustment of the mechanism so as to regulate the rate of discharge may be easily and accurately effected; this application being a 30 divisional application of my co-pending application Serial No. 830,744, filed April 9, 1914.

The invention consists in the novel construction, arrangement and combination of 35 various devices and parts, as shown in the accompanying drawings and hereinafter particularly described.

In the said drawings, Figure 1 is a side elevation of a car constructed according 40 to my invention; Fig. 2 is a sectional view thereof taken on the line 2—2 of Fig. 1; and looking in the direction of the arrows; Fig. 3 is a detail view, hereinafter more particularly described, Fig. 4 is a sectional view 45 taken just to the left of the flange 80 shown in Fig. 5 and looking from the right, and Fig. 5 is a perspective and diagrammatic view showing certain positions of my invention.

50 In carrying my invention into effect in the embodiment thereof which I have selected

for illustration in the accompanying drawings and description in this specification, I provide for the lower part of the car a running gear of the common or any suitable 55 form of construction, comprising the usual sills and bolsters, which are mounted on two bogie trucks, provided with journal boxes, numbered 13 in the drawings, which form the bearings for the ends of the axles 60 14.

The upper or carrying portion of the car is pivotally elevated above the running gear above referred to by the construction hereafter to be described. This carrying portion 65 comprises a floor 15, to the under side of which are secured spreader plates provided with trunnions 19, bearing in openings 18 in spreader plates 17. The floor is provided with ends 51, and sides 47 and 48, these 70 sides preferably being capable of being elevated for discharging the load, but as this feature is described and claimed in a co-pending divisional application of said application No. 830,744, they are not particularly described, or claimed, herein.

When the body of the car is in its normal erect or carrying position, as shown in the drawings, it is so held by the chains 60 and 61 which are attached to the body of the 80 car, and which pass downward and under and around pulleys 63 and 62 respectively and then pass horizontally to the end of the car and are wound for a portion of their 85 length around a windless shaft 36. It is desirable that other supporting means be also used to hold the body in its erect or carrying position but as means for this purpose are described and claimed in said co-pending original application No. 830,744, they 90 are not particularly shown, or described and claimed in this application.

It is desirable that the tilting of the car body be effected by power mechanism. Such mechanism may consist of a cylinder 56 for 95 compressed air or the like, operatively connected with the car body in such a way as to tilt the same when the piston of said cylinder is moved, the chains 60 and 61 being of course first released. As this mechanism is 100 described and claimed in applicant's said co-pending divisional application, it is

merely mentioned here. As heretofore stated, the said chains 60 and 61 are wound for a portion of their length in the same direction around the windlass shaft 36. Referring particularly to the detail view Fig. 3 it will be seen that the end of this shaft 36 is squared, so as to receive a crank for rotating same to wind up the chains when it is desired to restore the car body to its normal position after dumping, and it will be obvious that upon rotating this shaft and winding up both of said chains thereon until they are quite taut, the upper side of the tilted body will be drawn down by one of the chains, the slack of the other chain being at the same time taken up, and that when the body becomes level both chains will be tight. When this occurs the car body will be held in its horizontal position by the two chains, which will be held from unwinding by the ratchet mechanism now to be described.

The shaft 36 is journaled in the brackets 32, and to each of these brackets is pivoted an arm 70. Pivottally secured to the outer end of these arms 70 are pawls 31 and 31^a. At the same points are pivottally secured the lower ends of rods 72, the upper ends of which are pivottally secured to levers 75, having handles 25. Each lever 75 is pivottally secured in a bracket 74, and it has a pivotal lock 27, secured to the lever 75 at 28, the lower end 29 of which engages with a rack provided with notches 30, being held in engagement therewith by a spring 31', in a manner which will be well understood.

There are two ratchet wheels 33 and 33^a (provided with flanges 80, 81, 82 and 83) on the shaft 36, the teeth of which are in register with each other a pawl for each ratchet and operating devices therefor. The said pawls are of different lengths (see Fig. 4) so that at any one time only one of said ratchets is in engagement with a pawl. When one of the pawls is disengaged from its corresponding ratchet wheel the shaft is free to unwind to the extent of one-half the distance between the teeth, being stopped after rotating to that extent by the other pawl and ratchet. If then the second pawl and ratchet are disengaged and the first thrown into engagement, the shaft can unwind another half-tooth, and so on. This enables the car to be either tilted to its full extent quickly, by disengaging both pawls and ratchets, thus allowing the restraining chain to quickly unwind to the fullest extent, or to be tilted a very small distance and held there or successively tilted more and more step by step, by disengaging said pawls and ratchets alternately, keeping one set in engagement while the other set is disengaged. As both chains are wound upon the shaft in the same direction, it follows that both are tightened and both released

at the same time. As both chains are slackened, the car is free to tilt in whichever direction is desired.

The operation and advantages of my invention will be readily understood from what has been above said with regard to its construction.

Having thus described my invention, what I claim as new and desire to secure by Letters Patent is as follows:

1. In a dumping car, the combination with a car body, running gear, and means adapted to pivotally support said body upon said running gear; of means adapted when in one position to maintain said body horizontal and when in another position to allow said body to tilt, said means comprising a chain secured to said car body on each side of the middle line thereof, and means adapted to hold or release both of said chains at the same time.

2. In a dumping car, the combination with a car body, running gear, and means adapted to pivotally support said body upon said running gear; of means adapted when in one position to maintain said body horizontal, when in another position to allow said body to partially tilt, and when in another position to allow said body to tilt to its full extent, said means comprising a chain secured to said body on each side of the middle line thereof, and means adapted to hold, partially release, or fully release both of said chains at the same time.

3. In a dumping car, the combination with a car body, running gear, and means adapted to pivotally support said body upon said running gear, of means adapted to maintain said body in a horizontal carrying position, comprising a chain one end of which is secured to said car body and the other end of which is secured to a rotatable shaft and a portion of which chain is adapted to be wound upon said shaft, a plurality of ratchet wheels upon said shaft, a pawl adapted to engage with each of said ratchet wheels, one of said pawls being longer than the other, and means adapted to disengage either of said pawls from its ratchet respectively.

4. In a dumping car, the combination with a car body, running gear, and means adapted to pivotally support said body upon said running gear; of means adapted to maintain said body in a horizontal carrying position comprising a chain secured to said car body on each side of the middle line thereof, the other ends of which chains are secured to a rotatable shaft and a portion of each of which chains is adapted to be wound upon said shaft, a plurality of ratchet wheels upon said shaft, a pawl adapted to engage with each of said ratchet wheels, one of said pawls being longer than

the other, and means adapted to disengage either of said pawls from its ratchet.

5. In a dumping car, the combination with a car body, running gear, and means adapted to pivotally support said body upon said running gear; of means adapted to support said body in a horizontal position, comprising chains 60 and 61, secured to said car body at the sides of the middle line thereof, the other ends of which chains are secured to a rotatable shaft 36 and portions of which chains are adapted to be wound upon said shaft, ratchet wheels 33 upon said shaft 36, a pawl adapted to engage with each of said ratchet wheels, one of said pawls being longer than the other, and means adapted to disengage either of said pawls from its ratchet.

6. In a dumping car, the combination with a car body, running gear, and means adapted to pivotally support said body upon said running gear; of means adapted to maintain said body in a horizontal carrying position, said means comprising a chain secured to said car body on each side of the middle line thereof, the other ends of said chains being secured to a rotatable shaft, a portion of each of said chains being wound around said shaft in the same direc-

tion, a ratchet wheel on said shaft a pawl 30 engaging with said ratchet wheel, and means adapted to disengage said pawl from said ratchet.

7. In a dumping car, the combination with a car body, running gear, and means adapted to pivotally support said body upon said running gear, of means adapted to maintain said body in a horizontal carrying position, comprising a chain secured to said car body on each side of the middle line thereof, the other ends of which chains are secured to a rotatable shaft and a portion of each of which chains is adapted to be wound upon said shaft in the same direction, a plurality of ratchet wheels on 45 said shaft, a pawl adapted to engage with each of said ratchet wheels, one of said pawls being longer than the other, and means adapted to disengage either of said pawls from its ratchet. 50

In witness whereof I have hereunto signed my name this 31st day of October, 1914, in the presence of two subscribing witnesses.

WILLIAM D. SKIDMORE.
